COMBINATION DOUBLE HUNG AND CASEMENT WINDOW AND MEANS TO ADJUST SAME

George Simpkins and Wynne T. Ramsey,
Long Beach, Calif.

Application August 19, 1948, Serial No. 45,166

2 Claims. (Cl. 189—72)

1

This invention relates to a combination double hung and casement window, and particularly to a means to adjust the double hung window sashes, the adjustment being accomplished by means of a crank which can be inserted into a pulley.

An object of our invention is to provide a novel combination double hung and casement window in which the adjusting cable for the double hung sash extends through the sash itself.

A feature of our invention is to provide a novel combination double hung and casement window of the character stated in which the control cable extends through the upper and lower sashes thus providing a window which can be caused to move vertically with little effort, and which can be cranked up or down by a small crank inserted into an operating pulley.

Another object of our invention is to provide a novel window of the character stated in which the sash of the double hung window is slidably mounted in the casement, and pulleys are mounted in the sash, engaging the casement, thus preventing the sash from tilting in the casement.

Another feature of our invention is to provide a novel window of the character stated which is particularly adapted to metal construction. The various jambs, sills, headers, casements, and sashes are preferably formed of metal, that is, various metal shapes which can be either castings or extrusions.

Still another feature of our invention is to provide a novel means of mounting the pulleys in the sash of the double hung windows.

Other objects, advantages and features of invention may appear from the accompanying drawing, the subjoined detailed description and the appended claims.

In the drawing:

Figure 1 is a fragmentary front elevation of our novel window.

Figure 2 is a fragmentary perspective view of the casement showing the latch.

Figure 3 is a fragmentary sectional view taken on line 3—3 of Figure 1.

Figure 4 is a front elevation of our window with parts broken away to show interior construction.

Figure 5 is an edge view of our window with parts broken away to show interior construction taken on line 5—5 of Figure 4.

Figure 6 is a fragmentary end view as viewed from the line 6—6 of Figure 4.

Figure 7 is a fragmentary side view of the double hung window sash with parts broken away to show interior construction.

Figure 8 is a fragmentary edge view of the double hung window sash.

Figure 9 is a fragmentary sectional view taken on line 9—9 of Figure 4.

Figure 10 is a fragmentary end view of the casement.

2

Figure 11 is a fragmentary sectional view taken on line 11—11 of Figure 4.

Referring more particularly to the drawing, our combination double hung and casement window includes a sill 1, and jambs 2, 2, rising from this sill. The jamb and sill are mounted in the wall of the house in the usual and well known manner. We preferably fabricate the sill and jambs of metal parts and these metal parts are standard shapes and they may be either castings or extrusions. The sill 1, is formed with a shoulder or ledge 3, and the purpose of this shoulder will be subsequently described.

A casement 4, is hingedly mounted to a jamb 2, by the hinges 5, 5. We thus provide a swinging casement, all of which is usual and well known in the art. The casement latch consists of a shaft 6, journaled in the casement, and rotated by a lever 7, fixedly attached to the shaft. A link 8, is fixed to the other end of the shaft 6, and this link is formed with a slot 9, into which the pin 10, extends. The pin 10, projects from the bolt 11, which is slidably mounted in the casement 4, substantially as shown in Figure 2. Thus, by swinging the lever 7, it is possible to move the bolt 11, into engagement with the jamb 2, or to free it from this jamb as desired. As far as described, it will be evident that the casement 4, can swing in the jambs 2, 2, in the usual and well known manner.

The upper double hung sash 12, and the lower double hung sash 13, are slidably mounted in the casement 4, for vertical movement. The casement 4, is provided with adjacent vertical grooves 14, and 15, to receive the sashes 12, 13, respectively. The usual glass panes 16, 17, are mounted in the sashes 12, 13, respectively. The sashes, 12, 13, are also preferably formed of metal, and are arranged in the usual shape, and may be either castings or extrusions. From an examination of Figure 3, it will be seen that the sash 13, in its lowermost position projects below the shoulder 3, in the sill 1. When the sash 13, is completely lowered as shown, the casement 4, cannot be opened. It is necessary to slightly raise the sash 13, before the casement can be swung on its hinges 5. The purpose of this arrangement is to act as a secondary latch for the casement part of the window. The double hung sashes 12, 13, are latched or held in closed position by means of the pin 18, which is threaded into the sash, 13, and projects into the hole 19, in the bottom of the sash 12. By unscrewing the pin 18, so that it is removed from the hole 19, the sashes 12, and 13, will be free to slide vertically.

The double hung sashes 12 and 13, move vertically in the grooves 14 and 15, and to guide these sashes in their movement, we provide rollers 20, at all four corners of each of the sashes. The rollers

20, are also pulleys, as will be further described, and to mount these pulleys in the metal sashes, 12 and 13, we provide a frame and reenforcing angle, 21. Since the pulleys 20, are all mounted in an identical manner, only one will be described. The frame 21, is formed as an angle and accurately fits the channel of the sashes 12, and 13. Each frame 21, has a groove 22, cut in its outer corner and this groove is just wide enough to receive the pulley 20. The frame 21, is securely fastened in the channel of the sashes 12 and 13, by means of rivets or screws, or similar fastening means, 23. Thus the angle 21, serves to reinforce each corner of the sashes 12 and 13; and also supports the pulleys 20, on their pins 24, which enters the frame, 21, as shown. The pulleys 24, protrude slightly beyond the lateral edges of the sashes 12 and 13, and thus bear against the casement 4, thereby providing a roller bearing for the sashes 12 and 13, and also preventing these sashes from tilting as they are moved vertically.

The upper sash 12, is moved by means of the cable 25, and the lower sash 13, is moved by the cable 26. The method of stringing the cables 25, and 26, is identical, and consequently the course of only one will be described in detail. The cable 25, for example, is secured at one end to a spring 27, the other end of this spring being fixedly secured to the casement 4, at one side, substantially as shown in Figures 4 and 10. The cable then passes around a sheave 28, which is also journaled in the casement 4. After passing around the sheave 28, the cable passes upwardly within the channel of the sash 12, and thence over the two upper pulleys 20, and then downwardly where it is wrapped once around a second sheave 29, then over the two lower pulleys 20, and is finally tied or fixedly secured to the casement 4, adjacent the sheave 28, and as shown at 30. The sheave 29, is rotated manually by a crank 31, which is inserted into the sheave through the wall of the casement 4, the sheave being suitably shaped to receive this crank. By rotating the crank 31, the sheave 29, is rotated; thus moving the cable 25, and causing pressure to be exerted on either the top or bottom of the sash 12, depending upon the direction of rotation of the sheave 29, that is, the double hung sash 12, or 13, can be moved upwardly or downwardly depending upon the direction of rotation of the sheave 29, which controls the cable encircling the window.

Notice that the control cable is attached at one end to the spring 27, which maintains a constant tension on the cable, and the cable then extends around the four sides of the sash 12 or 13, and within this sash, that is, the channel construction of the sash also acts as a conduit for the cable. In operation the pin 18, is first retracted so that it is free of the hole 19. The crank 31, is now engaged with either of the sheaves 29, depending on which sash is to be moved. Assuming the upper sash is the one to be lowered, the crank 31, is rotated, thus rotating the sheave 29, and causing pull to be exerted on the cable 25. This

downward pull on the cable is transmitted to the rollers 20, and the sash 12, moves downwardly. The sheave 29, is rotated in the opposite direction to raise the sash 12. The rollers 20, at the four corners of the sash will prevent tilting of the sash in its guides, and consequently, the sash will move vertically with very little effort on the part of the operator.

To open the casement 4, the lower sash 13, is raised slightly so that the lower edge of the sash is above the shoulder 3, as shown in Figure 3. The casement 4, can now be swung on its hinges 5, as desired. A friction bar 32, is pressed against the shaft 33, of the sheave 29, thus exerting a braking action on this sheave so that the sash 12 or 13, will remain in its adjusted position. Since the cable is wrapped around the operating sheave 29, this sheave can slip relative to the cable if enough force is exerted and this is advantageous in event that too much force is exerted on the crank 31. If this occurs, the sheave 29, will slip without injuring the cable.

Having described our invention, we claim:

1. In a double hung window comprising a frame, and a pair of metal sashes slidably mounted in said frame, said metal sashes being hollow, a pulley journaled at the corners of each of the sashes, a pair of sheaves journaled in the frame one on each side of the metal sashes, a cable extending over each of the sheaves, and over said pulleys; said cable extending within the hollow metal sash, means to manually rotate one of said sheaves whereby one of the metal sashes is moved vertically.
2. In a double hung window comprising a frame, and a pair of metal sashes slidably mounted in said frame, said metal sashes being hollow, a pulley journaled at the corners of each of the sashes, a pair of sheaves journaled in the frame one on each side of the metal sashes, a cable extending over each of the sheaves, and over said pulleys; said cable extending within the hollow metal sash, means to manually rotate one of said sheaves whereby one of the metal sashes is moved vertically, said pulleys engaging the inside of the frame to serve as guides for the sashes.

GEORGE SIMPKINS.
